R. L. SHERROD

SCRUBBING BOARD

Filed Feb. 26, 1927

ROBERT L. SHERROD,
By B. P. Hubbard

Attorney

UNITED STATES PATENT OFFICE.

ROBERT L. SHERROD, OF BROWNSVILLE, TENNESSEE, ASSIGNOR OF ONE-SIXTH TO G. G. MULHERRON, ONE-SIXTH TO TED MARTIN, ONE-SIXTH TO F. W. WHITEHURST, ONE-SIXTH TO T. D. GOOCH, AND ONE-SIXTH TO ROY S. MOORE, ALL OF BROWNSVILLE, TENNESSEE.

SCRUBBING BOARD.

Application filed February 26, 1927. Serial No. 171,265.

My invention relates to improvements in scrubbing boards.

An important object of the invention is to provide a scrubbing board which is simple in construction, cheap to manufacture and extremely durable.

10 A further object of the invention is to provide a scrubbing board, the rubbing elements of which are in the form of round surfaces whereby the possibility of injury to the wash is prevented.

15 A further object of the invention is to provide a scrubbing board having means for holding or retaining the water and soap, to a considerable extent, in proximity to the rubbing elements, whereby this water and soap is passed to or through the articles being washed, thus effecting a thorough washing action.

20 Other objects and advantages of the invention will be apparent during the course of the following description.

In the accompanying drawings, forming a part of this specification, and in which like numerals are employed to designate like parts throughout the same,

Figure 1 is a front side elevation of a scrubbing board embodying my invention,

30 Figure 2 is an edge elevation of the same, Figure 3 is an elevation of the inner side of one of the sides or legs of the scrubbing board embodying my invention,

Figure 4 is a longitudinal section taken on line 4-4 of Figure 1,

35 Figure 5 is a transverse section taken on line 5-5 of Figure 1, and,

Figure 6 is a perspective view of one of the rubbing elements or rods.

In the drawings, wherein for the purpose 40 of illustration, is shown a preferred embodiment of my invention, the numeral 10 designates the side bars or legs of the scrubbing board which are rigidly connected at their

45 top by a transverse bar or head 11, these parts constituting the frame of the scrubbing board. These parts are preferably formed of wood although they may be formed of other suitable material.

The side bars or legs 10 are provided upon 50 their rear faces with longitudinal recesses 12, and the upper portion of these recesses

have forward walls 13, and their lower portions forward walls 14, arranged in advance of the forward wall 13, there being a shoulder 15. These recesses have side walls 16, 55 extending throughout their entire length, and end walls 17, at the lower ends thereof. The inner face 18 of the head 11 constitutes the upper end walls of these longitudinal recesses, and this inner face has a transverse 60 groove 19, leading into these recesses, adjacent to the forward walls 13.

Adapted for insertion within the longitudinal recesses 12 are longitudinal clamps or strips 20, preferably formed of wood, while 65 any other suitable material may be employed. These clamps are provided in their upper portions with straight forward walls or faces 21 and in their lower portions with straight forward walls or faces 22, positioned rearwardly of the walls 21, there being a shoulder 23. The walls 14 and 22 are spaced laterally a greater distance than the walls 13 and 21, as shown. The body portion of the scrubbing board is formed of a 70 sheet 24, preferably twenty-eight gauge galvanized sheet iron, although any other suitable material may be employed. The extreme upper end of this sheet is bent upon itself, forming a reinforcing and stiffening 75 bead 25, Figure 4, and this bead is adapted for insertion within the groove 19. Spaced downwardly from this bead, the sheet 24 is bent upon itself to provide a two-ply soap tray or flange 26. This tray is formed by 80 bending the metal upon itself at the outer point 27, and then at inner points 28, forming sections or plys 29, arranged in close contacting relation. This tray or flange is slit transversely at its ends and inwardly of 85 and adjacent to the inner edges of the sides 10, as indicated at 30, forming sections 31, which are bent down flat upon the sheet 24, and the walls 12 are recessed at 32, to receive these extensions. 90

The lower portion of the sheet 24 beneath the soap tray 26 is bent rearwardly and laterally to form forward transverse grooves or pockets 33 which are spaced suitable distances apart. I have found that satisfactory 100 results may be obtained by having these pockets spaced anywhere from three-fourths

2
of an inch to one inch apart, although the invention is not restricted to these precise dimensions. These pockets have inclined longitudinal bottom walls 34 and transverse bottom walls 35, which are preferably perpendicular to the longitudinal axis of the sides 10. These pockets are so shaped that when the scrubbing board is occupying the inclined position, in the scrubbing operation, 10 that they will hold the water and soap, and supply the same to the article being washed.

The numeral 36 designates rubbing elements or rods, each of which is formed of a plurality of closely twisted elements 37. I 15 prefer to use number 12 galvanized wire, while the invention is not necessarily restricted to this material. By twisting these wires closely an element or rod is provided which is substantially rigid and presents a 20 plurality of closely associated circularly curved rubbing surfaces or faces. The rubbing element or rod is preferably made up of four sections of wire 37.

The rubbing elements or rods 36 are placed 25 within the pockets 33 and the all-over diameter of these elements is such that they project forwardly beyond the forward shoulders 35, for a substantial distance, whereby they take substantially all of the rubbing 30 action. These rubbing elements have a length substantially equal to the length of the pockets 33. The sheet 24 with the rubbing elements within its pockets, are introduced into the longitudinal recesses 12, the 35 straight upper portion of the sheet 24 being clamped between the walls 13 and 21, while the rubbing elements 36 engage the walls 14, and the bottom of the pockets 35 engage the wall 23. The clamps or strips 20 are attached 40 to the side bars 10 by means of screws 39 or the like. By this means the sheet 24 and the rubbing elements are securely mounted within the frame of the scrubbing board. Of course, the strip 20 may be removed at any 45 time, should it be desired to remove the sheet 24 and rubbing elements 36. The arrangement is such that the strips 20 effect a substantially uniform clamping action with the sheet 24 and the rubbing elements 36.

50 In the use of the device, the scrubbing board is arranged in an inclined position, as is customary. The articles to be washed are rubbed upon the upper surface of the board in contact with the rubbing elements or rods 36. As these rubbing elements extend forwardly beyond the surfaces of the pockets, the major portion of the rubbing is effected upon these elements. As the elements are formed of closely twisted strands of wire, 55 they present the maximum number of rubbing faces, all of which are circularly curved.

The tightly twisted rubbing elements are substantially rigid and are adapted to offer the proper resistance to the articles being washed, without liability of the articles be-

coming caught between the turns of the same. The pockets are adapted to hold the soap and water, and transmit the same to the articles being washed, to aid in their proper cleansing.

70 It is to be understood that the form of my invention, herewith shown and described, is to be taken as a preferred example of the same, and that various changes in the shape, size and arrangement of parts 75 may be resorted to without departing from the spirit of my invention, or the scope of the subjoined claims.

Having thus described my invention, I 80 claim:

1. A scrubbing board comprising side bars, a sheet arranged between and carried by the side bars, said sheet having its material bent to provide spaced transverse water receiving pockets, having forward shoulders, and rubbing elements held within the water receiving pockets, each rubbing element being formed of a plurality of tightly twisted strands of wire, the rear sides of each rubbing element being arranged rearwardly of the forward shoulder of the corresponding pocket, the outside diameter of each rubbing element being sufficiently large so that the forward side of the rubbing element projects 90 forwardly beyond the shoulder of the pocket 95 for free engagement with the articles being washed.

2. A scrubbing board comprising side bars, a sheet arranged adjacent to said side bars and having its material bent to provide spaced transverse pockets, rubbing elements held within the pockets, each rubbing element being formed of a plurality of tightly twisted strands of wire, the outside diameter 100 of each rubbing element being sufficiently large so that the rubbing element projects laterally outwardly beyond the pocket, and clamping strips engaging the rear sides of the pockets and forcing the ends of the rubbing elements into engagement with said side bars.

3. A scrubbing board comprising connected side bars having longitudinal recesses, a sheet inserted within said recesses and provided in its lower portion with rearwardly bent spaced pockets, rubbing elements arranged within said pockets, each rubbing element including a plurality of tightly twisted sections of wire, the outside diameter 110 of each rubbing element being sufficiently large to project laterally beyond the pocket to engage with the walls of the recesses, and clamp strips arranged behind said sheet and engaging with the rear side of the upper portion of the sheet and with the rear sides of 115 said pockets.

4. A scrubbing board comprising connected side bars, a sheet secured to said side bars, said sheet being bent to provide transverse spaced pockets facing forwardly, said 120

pockets having lower end walls which are substantially perpendicular to the longitudinal axis of the sheet whereby such pockets are adapted to hold water, and rubbing elements arranged within the pockets, each rubbing element being formed of a plurality of sections of closely twisted wire, the out-

side diameter of each rubbing element being sufficiently large so that the rubbing element extends laterally beyond the forward side of 10 the pocket for a substantial distance.

In testimony whereof I affix my signature.

ROBERT L. SHERROD.
